AUTOMOBILE BODY

Application filed May 25, 1929. Serial No. 365,874.

The present invention relates to automobile bodies and more particularly to the doors, sashes and door frames. The object of the invention is to provide a body for automobiles which may be readily converted for use either as an open or a closed body. Heretofore, various folding tops and folding curtains have been provided for making automobile bodies convertible from open to closed 10 and vice versa. The object of the present invention is to provide a body which may be quickly converted from open to closed, or vice versa, and which will have all of the characteristics and advantages of an open 15 body when converted to that use and which will have all of the advantages and appearance of a closed body when converted for that use. When used as a closed body there may be any number of side doors at each side, 20 two being shown in the drawings, and each door has its individual sash or glass which may be raised and lowered by well known devices now in common use for the purpose of ventilation or for entirely closing the car 25 to exclude rain, snow and wind. These sashes, while the car is used as a closed car, therefore, operate the same as the sashes of the standard closed bodies. The sash frames while the body is used as a closed one are 30 firmly held in position against shaking or rattling, so that they are substantially as rigid in relation to the door as the corresponding sash frames of standard bodies.

The sashes are adapted to slide vertically 35 into and out of vertical pockets in the door and to slide vertically in suitable grooves in the sash frame above the door. The sash frames also move as integral parts of the door when the latter is being opened and closed. 40 In all respects, therefore, the door, sash and sash frame all operate similar to the corresponding members of closed bodies now in general use.

To convert the body to an open one it is 45 only necessary to move the sashes into the door pockets, swing the sash frames downwardly into suitable recesses in the door, whereupon the sash and sash frames will be hidden from view, and contained within the 50 door structure, so that the latter will then

operate the same as the doors ordinarily employed in open automobile bodies. In the full embodiment of my invention the side post or stanchions interposed between the front door and sash and the rear door and sash, where the body is provided with both front and rear doors, may also be folded down so that the upper portions of these posts or stanchions are contained within suitable pockets in the lower portions of the post or stanchions. When this feature of the invention is employed in conjunction with those first referred to the body, when converted for open use, will provide a clear and unobstructed side opening at each side of the vehicle above the doors, so that it will have the appearance of an open or touring body.

Another object of the invention is to provide means for preventing the sash frames from being folded down until the sashes have 70 been moved into the door pockets.

Another object of the invention is to provide a body which may be very quickly converted without taking apart the doors or sash frames and to provide a construction which permits the conversion from one type of body to the other to be made by one person acting alone and while stationed inside the vehicle. With the present invention it is possible to obtain all the advantages of a convertible body and at the same time use glass sashes or windows and to have the latter protected against breakage when the body is used as an open one. The sashes and their frames remain attached to and are movable with the doors at all times whether the body is used as an open or closed one. There are various other objects and advantages which will be set forth more in detail in the following description of one embodiment of my invention.

In the drawings forming part of this application,

Figure 1 is a side elevation of an automobile provided with a convertible body employing my invention,

Figure 2 is a front elevation on an enlarged scale of one of the doors and a portion of the body of the vehicle with parts broken away to illustrate the construction,

Figure 3 is a sectional view taken on the

line 3—3 of Figure 2 and showing the sash being moved into the door pocket,

Figure 4 is a sectional view taken on the line 4—4 of Figure 2,

Figure 5 is a plan view of the parts shown in Figure 2,

Figure 6 is a perspective view showing a portion of the automobile body, one of the doors and the intermediate post or stanchion between the doors at one side of the body,

Figure 7 is a similar view of the same parts but illustrating the same converted for use as an open or summer body,

Figure 8 is a sectional view taken on the line 8—8 of Figure 13,

Figure 9 is a top view of the same parts shown in Figure 8.

Figure 10 is a front elevation of a door frame construction with the door removed and illustrating the manner of folding and extending the movable members of a door frame,

Figure 11 is a sectional view taken on the line 11—11 of Figure 10,

Figure 12 is a perspective view of some of the members of a door frame,

Figure 13 is a sectional view taken on the line 13—13 of Figure 10,

Figure 14 is a sectional view taken on the line 14—14 of Figure 10,

Figure 15 is a perspective view of a portion of the door frame,

Figure 16 is a plan view of the member shown in Figure 15,

Figure 17 is a front elevation of one of the doors with the sash frame in extended position and the sash raised to form a full closure,

Figure 18 is a sectional view taken on the line 18—18 of Figure 17,

Figure 19 is a face view of the inner side of one of the doors showing the same converted for open body use,

Figure 20 is an edge view of one of the doors and its sash frame when in position for open body use, and

Figure 21 is an elevation of the inner side of one of the doors with parts broken away to show the interior mechanism, in which view the door is shown in position for closed body use.

The principal features of my invention may be incorporated in but one of the doors and sash frame of the entire vehicle, but preferably it is embodied in all of the doors in order that the body as a whole may be converted. In such case, however, the parts are more or less a mere duplication in respect to each door, but the door frame is preferably made foldable where more than one door on the same side of the body is made convertible. The following description, therefore, of the folding parts of one of the doors is applicable to all of the doors of the vehicle where they

are all supplied with the convertible features. The front post or stanchion just in advance of the foredoor of the body is preferably made rigid or permanent.

I have shown an automobile of the type having front and rear doors at each side and it is to be understood that the particular type of body may be varied as the present invention requires only modification of the doors and their stanchions or posts. I have shown a door 1 supported by the usual hinges 2 upon a side post or stanchion of the vehicle body; and in the case of the front door these hinges are mounted on the solid or immovable section 45 of the intermediate post or stanchion which is disposed between the front and rear doors on one side of the body; whereas, in the case of the rear door the hinges 2 are preferably mounted on the rear stanchion 4 of the vehicle. This arrangement is not imperative because if desired the front door may be hinged to the front stanchion 5. Both methods of disposing the hinges are now in common use. The door comprises the lower or panel section 6 which is generally curved or shaped to conform to the contour of the lower portion of the body of the vehicle on its exterior surface and for this reason I have shown the outer plate or panel of the door curved to conform to the shape of the body.

This lower or panel portion of the door extends but partway of the height of the car, the top of the panel section of the door usually extending about to the top line of the seatbacks, although the proportions of the door may be varied in the present case the same as with doors on standard types of vehicles now in general use. The panel or lower portion of the door generally made of metal, is shown as consisting of the outer panel 6, the top wall 8 which is provided with a longitudinal slot 9 and having a downwardly extending flange 10 adjacent the edge of the slot; a rear wall 12 and end walls 13, together forming a chamber or pocket 14 for the reception of the sash and various devices co-operating with the sash. The end walls 13 of the door are preferably vertical and flat, although variations in regard to the shape of these walls may be made without departing from the spirit of my invention. These end walls are adapted to lie flush against the side posts or stanchions when the door is in closed position. These end walls are provided with cut-outs or recesses 15 which extend inwardly from the edges of each end wall to provide recesses to receive portions of the sash frame and the bottom of these recesses is defined by the walls 16 which are shown as formed from the same metal as the inner walls 12 of the door. This leaves a recess countersink at each end of the door and extending vertically from the point 18 to a point adjacent the bottom of the door. Near the bottom of the door the metal of the door is bent inwardly, down-

wardly and outwardly, as shown at 19, to provide a pocket or recess 20 extending longitudinally along the door and communicating at each end with the vertical recesses or pockets 15. In describing these recesses as formed by bending the metal it will be understood that they may be formed in any other manner.

The above parts, except for the mechanism contained within the pocket 14 constitute the lower or panel section of the door and the same applies to each door of the vehicle which is supplied with the features of my invention except that in the case of a rear door, as shown in Figure 1, one corner may be rounded as shown at 21 to conform with the curvature of the rear mud guard in which case, however, the other features above described will nevertheless be present.

The sash section of the door comprises a swinging frame consisting of the vertical or upright members 22 adjacent each end of the door and connected by a top cross member 23, these three members being, preferably, formed integral by bending a continuous piece of metal to form three sides of a rectangle. The inner sides of both the vertical members 22 and preferably the horizontal member 23 are each provided with a groove 24 the groove of all three members being in a common vertical plane, so that the sash may engage in and slide through the groove of the vertical members and the top edge of the sash may enter into the groove of the horizontal member 23 to form a water-excluding relation between the movable sash and the sash frame. The lower ends of the vertical members 22 of the sash terminate in flat plate portions 25 which have lateral extensions 26 projecting inwardly of the vehicle and these extensions are provided with oblique slots 27 which receive therethrough the pintles 28 which are fixed to the body of the door and serve as hinges for the sash frame to pivot upon. These slots 27 permit the vertical members 22 of the sash frame to lie flush with the outer surface of the door when in raised or active position and by a lateral shifting of the sash frame when the latter is swung downwardly they permit the vertical members to move inwardly of the door, so as to lie in the end recesses 15, as will be further pointed out.

When the sash is in the raised or active position the several grooves 24 in the vertical and horizontal members all lie in the same plane with the sash slot 9 in the top plate of the lower section or body of the door. The vertical members 22 of the sash frame have shoulders 29 formed adjacent the plate extensions 25 so that when the sash frames are in their extended or raised position, these shoulders will rest upon the top wall 8 of the body of the door as shown in Figures 17, 20 and 21 in order to relieve the

pintles 28 of the weight of the sash frames when they are in active position.

The sash 30, which is preferably made of glass, is adapted to move vertically through the slot 9 in the top wall of the door with its ends traveling in and guided by the grooves 24 of the vertical members 22 of the sash frame. This vertically sliding sash is adapted to lie entirely within the chamber 14 of the door when in its lowermost position and is adapted to be raised through the slot 9 of the door and upwardly until the top edge lies in the groove 24 of the horizontal member 23 of the sash frame to form a complete closure between the body of the door and the several members of the sash frame.

This sash may be raised and lowered by the same mechanism which is now in general use for moving the sliding sashes of present types of doors and I have merely indicated the interior crank handle 31 of such mechanism because the same needs no modification for employment in the present arrangement. I have provided means for automatically locking the sash frame in its upper or raised position, which locking means is adapted to be unlocked by the movable sash. There is a bracket 32 mounted inside the compartment 14 of the door at each end thereof, which brackets, together with fixed blocks 33 form guides for the sliding, locking pins 34 which are adapted to project through the end walls of the door and engage in the apertures 35 of the lateral plates 26 of the sash frame.

There is a coiled spring 36 surrounding each of these locking pins 34 which springs are compressed between the bracket 32 and a collar 37 on the pin 34 for the purpose of projecting the pin outwardly through the aperture 35. The inner end of each pin 34 is shown provided with flanges 38 between which engages a fork 39 on the end of the bell crank lever 40 which is pivoted on the pin 41. One arm of each bell crank lever has pivoted to it a link 42 which extends downwardly within the pocket 14 of the door and on its lower end each link has a lateral projection 43 preferably lined on its top surface with a pad 44 with which the lower edge of the sash 30 is adapted to engage so that as the sash approaches its lowermost position within the pocket 14 of the door it engages the pair of links 42 and exerts a downward movement on them to rock the bell crank levers 40 and by this action withdraw the locking pins 34 within the end walls of the door to disengage them from the apertures 35 of the sash frame. This unlocks the sash frame to permit it to be turned upon its pintles 28. The links 42, in addition to transmitting the motion to the bell crank levers, serve as supports for the sash when the latter is in its lowermost position.

There are apertures 35a in the members 26 opposite the apertures 35, and these will lie

opposite the locking pins 34 when the sash frame is folded down against the door. If, therefore, while the sash frame is in lowered or folded position, and it is attempted to raise the sash frame while the sash is partly raised, the latter would be injured, but this is prevented by the locking device the same as in the case of lowering the sash frame. If the sash frame is folded down and the sash is partly raised, the locking pins will be engaged in the apertures 35a and the sash frame cannot be raised and it will therefore not break the sash.

It will be necessary to lower the sash to release the locking pins 34 from the apertures 35a and the sash frame can then be swung upwardly without conflict with the sash. The locking device therefore serves to prevent the sash frame from being raised or lowered while the sash is partly or wholly raised or in other words, when the sash is in position where the sash and sash frame might interfere one with the other.

The features above described may be used regardless of the construction of the door frames or stanchions of the vehicle body. That is to say, they may be used in conjunction with the ordinary type of stanchion. However, in order to make the automobile body fully convertible I prefer to combine with the above features a folding or collapsible frame for the door, as follows:

The stanchion shown at 5 in Figures 1 and 6 may be a rigid or permanent stanchion similar to present constructions because in most cases it is desirable to have the front stanchions remain in fixed position even when the body is converted for open use. The stanchion intermediate the two doors of each side of the body are preferably made collapsible. The section 45 of the intermediate stanchion which extends to the top line of the panel portion of the doors, is a rigid portion of the body structure. The upper portion of the stanchion, when the latter is extended for open body use, includes the hinged member 43 with which the foredoor is adapted to co-operate; and a hinged member 47 with which the rear door co-operates. The member 47 consists of a flat plate section 48 having a flange 49 extending at right angles thereto to be overlapped by one end of the door. This stanchion member is provided with a lower extension 50 the width of which is less than the total width of the member 47, so that an offset or shoulder portion 51 is formed at the base of the member 47.

The lower end of the member 50 is provided with an aperture 52 through which projects the hinge pin 53 fixed in the rigid section of the stanchion. The pin 53 is of sufficient length to permit the member 47 to be shifted from the full line to the dotted line position in Figure 13, which distance corresponds with the depth of the shoulder 51.

The rigid section of the stanchion is provided with a pocket or recess 54. This recess or pocket is adapted to receive the hinged stanchion-members 46, 47 when the latter are swung downwardly into the dotted line position of Figure 13, so that these members lie within the pocket 54 flush with the side surface of the rigid section 45. 70

The member 46 is shiftable laterally along the hinge pin 53 in order that the outer edge 75 of the member 46 may lie flush with the outer surface of the rigid post section when it is in raised position, where the flange or side member 49 will be in proper position to permit the sash frame of the door to lie face 80 against it. When the member 46 is swung downwardly, however, it is shifted on the pin 53 to the dotted line position shown in Figure 13, in order to bring the swinging post section into line to be received into the 85 post pocket 54. There is a member 56 which forms a top horizontal section of the collapsible frame, one end of this member being pivoted on the pin 57 in the upper end of the rigid forward stanchion 5. This member is 90 adapted to be folded downwardly within the side pocket 58 of the rigid front stanchion in order to be out of the path of the swinging door when the body is converted for open use. When the body is arranged for closed 95 use the member 56 is swung upwardly on its pivot 57 and the free end of this member is dropped into a socket 59 in the upper end of the swinging post member 46 and the pin 60 disposed in this socket is received through an 100 aperture in the end of the horizontal member 56, as shown in Figure 6.

The folding stanchion member 47 which lies on the opposite side of the rigid portion of the stanchion to the folding member 46 105 is similar in most respects to the latter. This member 46 is also hinged on a pin 57 mounted in the rigid section of the rear stanchion 4. It has a lateral flange 49 and the bottom projection 50 which engages the hinge pin 53 110 as well as the offset or shoulder 51 adapted to rest upon the top of the rigid stanchion section. This member 47 is adapted, when in the raised position, to rest back to back in relation to the member 46 so that these two members constitute an upper section of the stanchion continuous with the rigid section 45. 115

The member 47 is adapted to be folded downwardly into the pocket 54 in the opposite side of the rigid section 45 to that of the member 46. This member is also adapted to be shifted laterally on its pivot pin 53 in order that the section may lie flush with the outer surface of the rigid section 45 and the door, and on the other hand to be folded within the pocket 54 when in lowered position. The top horizontal member 62 pivoted to the rear stanchion of the body is adapted 120 to be swung into horizontal position with the 125 130

free end resting on the socket 63 of the member 47 and with the pin 64 projecting through an aperture in the member 62.

Operation

- 5 When the body is arranged for closed use, as shown in Figure 1, the following conditions will exist: The foldable stanchion members 46, 47 will be in their raised position 10 lying back to back, as shown in Figures 4, 5 and 6, and the top members 56, 62 will extend across and connect the front rigid stanchion with the member 47, and the rear, rigid stanchion, with the member 46, so that the 15 rigid stanchions, together with the intermediate stanchion will form door frames for both the front and rear doors, and this will be true of both sides of the vehicle if the features described are duplicated at both sides. 20 If the vehicle body has but one side door at each side of the car, then the features described will be present only as to the single door on each side. The upper horizontal members 56, 62 will lie immediately below the 25 top 65 of the vehicle body, and it may be here noted that the top may be either a stationary one or a folding one in so far as the use of the present invention is concerned.

While the body is used as a closed one, the 30 sash frames, comprising the vertical members 22 and horizontal member 23 are in raised position, as shown in Figures 2 and 3, so that the shoulders 29 rest upon the top surface of the lower or solid portion of the door, with 35 the front surfaces of the sash frame flush with the front surface of the door. In this position the grooves 24 of the several members 22, 23 are all in the same vertical plane with the slot 9 in the top of the door. The sash 40 frame is locked in the position just described by the engagement of the locking pins 34 in the apertures 35 of the members 26. In this condition the door, together with the sash frame, may be swung open and closed and to 45 all appearances the door and its sash frame will be similar to the present type of door construction. The sash 30 may be raised and lowered through the slot 9 by operating the handle 31, the latter actuating the ordinary 50 sash raising and lowering device (not shown) and as the sash is raised or lowered, it not only moves through the slot 9 in the door, but it is guided at the sides in the grooves 24 and when the sash is in its uppermost position the 55 top edge enters the groove 24 of the horizontal member 23 of the sash, forming a weather-tight connection between the sash and its frame, in which case the door with its 60 sash and frame function exactly as if the folding features were not present. The door may be opened and closed, the sash frame moving as an integral part thereof, and the sash moves with the door and sash frame in 65 any vertical position in which it may be

placed; that is, whether it is partially or fully opened or entirely closed.

If the sash is moved downwardly it moves into the pocket or chamber 14 of the door. The same is true of each door which is supplied with the present improvements, although it will be understood that any of the doors may be separately converted, or, in other words, the rear doors of the vehicle may be used in closed condition while the front doors are used in folded or open condition or vice versa.

Assuming that the body is to be converted for open use, the following operations will be carried out, either in the order stated or in different sequence. The sash 30 in each door will be lowered by turning the cranks 31 until the sashes are entirely enclosed within the pockets 14. When a sash moves downwardly, just before it reaches its lowermost position it engages the cushions 44 on the portions 43 of the links 42 so that in its final movement the sash pulls downwardly on these links to rock the bell crank levers 40 and the forked ends of these levers act on the locking pins 34 to retract them in opposition to the springs 36 and thus withdraw the locking pins from the apertures 35. It will be obvious that it is desirable for the sash to operate the unlocking device in order to be certain that the sash is entirely within the door, and therefore entirely disengaged from the sash frame, before the latter can be swung on its hinge. The sash being now lowered within the door pocket 14 and the sash frame being unlocked by the pins 34 the sash frame as a whole is swung inwardly upon its pintles 28 and as it swings downwardly as indicated in Figure 6, the slots 27 permit it to move inwardly of the door so that when the sash turns downwardly against the inner face of the door the vertical members 22 will be received in the side pockets 15 and the horizontal member 23 will be received in the longitudinal pocket 20.

In other words, the sash frame is offset during its swinging movement so that when in raised position its outer surface will lie flush with the outer surface of the door and when in its lowermost position it will lie within the pockets 15, 20 and be flush with the inner surface of the door, as shown in Figure 19. The door may now be used as an open door; that is, without any sash or sash frame in operative position, so that the space above the solid portion of the door remains open. The same may be true of any or all of the doors of the vehicle body. If it is desired to remove the upper portion of the intermediate stanchion from view, the doors are temporarily swung open and the upper horizontal members 56, 62 of the door frame are first disengaged from the pins 60, 64 and the members 56, 62 are then swung downwardly, after the members 46, 47 have

been swung downwardly. The latter members are swung downwardly on their pins 57 before the members 56, 62 are folded until they lie within the stanchion pockets 58 and they remain in this position as long as the body is converted for open use. The stanchion members 46, 47 are swung downwardly in opposite directions, one toward the front and one toward the rear on their respective pins 53 and at the same time they are shifted laterally on these pins to bring them into register with the stanchion pocket 54, into which they are swung. When they are so positioned they lie flush with the side surfaces of the rigid portion of the stanchion and are out of the way of the swinging doors. During this lowering operation of the members 46, 47 they are shifted laterally on their pins 53 slightly different extents in order that when they are in their folded position the flange 49 of the member 46 will be received into the groove 70 of the member 47 in order that these members may be both folded in compact form within the pocket of the rigid stanchion section.

When the body has thus been fully converted for open use, the top 65 may be folded back if it is a folding top, or it may remain in the position shown in Figure 1, if it is a non-folding top. In either case, however, the sash frames are folded within the pockets on the inner side of the doors and the upper portions of the intermediate stanchion are folded within the pockets of the rigid portion of this stanchion so that there is an unobstructed view from the front stanchion 5 to the rear stanchion 4 of the body and the vehicle will have the appearance and function the same as an open or touring body.

The operations necessary to convert the body from open to closed, or vice versa, may be carried out by one or more persons either from inside the vehicle or outside the same. While each door sash is being folded or extended the particular door may be temporarily swung open for this purpose and also for the purpose of allowing the sash sections to be extended or collapsed. The complete operations necessary to convert the body from an open to a closed condition, or vice versa may be all carried out in a matter of a few minutes. It is unnecessary to detach any parts or to store them in different parts of the body because all parts are permanently attached and are always in condition to be converted.

Having described my invention, what I claim is:

1. A door for vehicles having a pocket for enclosing a sash, a sash slidable into and out of said pocket through the top thereof, said door having recesses at opposite sides and the bottom of said pocket and a sash frame pivoted to the upper portion of said door and adapted to be positioned vertically above

the door, and having grooves to form a guide for said sash when the latter is moved out of said pocket, said frame being adapted to be folded downwardly within the recesses in said door. 70

2. A door for vehicles having a pocket, a sash slideable into and out of said pocket, and a sash frame adapted, when in a vertical position above said door to form a guiding frame for said movable sash, and a hinge connection between said sash frame and said door which permits said sash to be placed in vertical position above said door or be folded down against the inner side of said door, said hinge connection permitting a limited lateral movement of said sash frame when moved between its raised and lowered positions. 75 80

3. A door for vehicles having a pocket, a sash slideable into and out of said pocket, and a sash frame pivoted to said door to be positioned vertically above the door to form a guide for said sash and to be folded downwardly against the inner side of said door, said door having recesses on its inner side to receive the members of said sash frame therein. 85 90

4. A door for vehicles having a pocket, a sash slideable into and out of said pocket, a sash frame pivoted to said door to be positioned vertically above the same to form a guide for said sash and adapted to be folded downwardly against the inner side of said door, means for locking said sash frame when in its raised position, and means operated by said sash for unlocking said sash frame to permit it to be folded downwardly against said door. 95 100

5. A door for vehicles having a pocket, a sash slideable into and out of said pocket, a sash frame pivoted to said door to be positioned vertically above the same to form a guide for said sash when the latter is moved out of said pocket and adapted to be folded downwardly against the inner side of said door, locking pins adapted to be projected into locking engagement with said sash frame to hold the same in vertical position, levers arranged in said door pocket for operating said locking pins, and means engaged by said sash when in its lower position for reTRACTING said locking pins. 105 110 115

6. A door for vehicles having a pocket, a sash slideable into and out of said pocket, a sash frame pivoted to said door to be positioned vertically above the same to form a guide for said sash and adapted to be folded downwardly against the inner side of said door, locking members in said door pocket adapted to lock the sash frame in its raised position, levers in said door pocket for reTRACTING said locking means, links pivoted to said levers and having portions on which the lower edge of the sash is adapted to rest when said sash is in lowered position, said 120 125 130

links being adapted to be operated by the lowering movement of said sash to release said locking means.

7. A vehicle body having a door frame including a stanchion composed of a lower, rigid section, an upper section pivoted to said rigid section whereby it may be positioned to form an upper extension thereof or be folded downwardly against the side of said rigid section, said rigid section having a side pocket to receive said pivoted stanchion section therein.

8. A vehicle body having a door frame, including a stanchion composed of a lower, rigid section having a recess in the side thereof, an upper stanchion section adapted to be positioned above said rigid section and to be folded downwardly into the recess in said rigid section, and means for pivoting said folding section of said stanchion to said rigid section to permit limited lateral movement thereof in relation to said rigid stanchion section.

9. A vehicle body having a door frame, including a stanchion composed of a lower, rigid section having a recess in the side thereof, an upper section having an offset portion adapted to lie flush with the exterior of said rigid stanchion section when in raised position, and means for pivoting said movable stanchion section to said rigid section and adapted to permit limited lateral movement of said movable stanchion.

10. A vehicle body having a door frame, including a stanchion composed of a lower, rigid section and an upper, movable section forming a continuation of the rigid section, said lower section having a recess to receive the upper section therein, said rigid stanchion section having a pin, said upper section having a member pivoted on said pin and adapted to slide thereon to permit limited lateral movement of said upper section, said upper section being adapted to be placed in a vertical position in relation to the rigid section or to be folded into said recess.

11. A vehicle body having door frames, including an intermediate stanchion forming parts of both door frames, said stanchion having a lower rigid section, a plurality of upper sections pivoted to said lower section and adapted to be swung in opposite directions and to be placed back to back in vertical position above the rigid sections of said stanchion and to be folded downwardly in opposite directions adjacent said rigid stanchion section.

12. A vehicle body having a door frame composed of spaced stanchions, a door hinged to swing between said stanchions, one of said stanchions comprising a rigid lower section, an upper section pivoted thereto to be placed in position to form an upper continuation of the lower section and to be folded down adjacent said rigid section, a top member for

connecting said stanchions, said top member being pivoted to one of said stanchions, said latter stanchion having a recess to receive said top member, and means for detachably connecting the end of said top member to said foldable stanchion section.

13. A vehicle body having a frame provided with a door opening defined by opposed stanchions, a door hinged to swing between said stanchions and comprising a lower section having a sash pocket, a sash frame pivoted to said lower door section to be placed in vertical position above the lower section or to be folded downwardly against the inner side thereof, a sash movable into and out of said door pocket and co-operating with said frame, at least one of said stanchions comprising a lower, rigid section conforming in height substantially with the height of the door and including a pivoted stanchion section co-operating with said sash frame.

14. A vehicle body having a frame provided with a door opening therein, at least one side of said opening being defined by a stanchion composed of a lower rigid section, an upper section adapted to be folded downwardly against said rigid section, and a sash frame mounted on said door to co-operate with said movable stanchion section, and means for pivoting said sash frame on said door to permit it to be folded down against the inner side of said door.

15. A door for vehicles having a pocket, a sash slideable into and out of said pocket, a sash frame pivoted to said door to be positioned vertically above the same to form a guide for said sash and adapted to be folded downwardly against the inner side of said door, means for locking said sash frame when in its lowered position and means operated by said sash for unlocking said sash frame to permit it to be swung in relation to said door.

16. A door for vehicles having a pocket, a sash slideable into and out of said pocket, a sash frame pivoted to said door and adapted to be positioned vertically above the door to form a guide for said sash and to be folded downwardly against the inner side of said door, locking means adapted to lockingly engage with said sash frame when the latter is in both its raised and lowered positions, and means operated by said sash to release said locking means.

Signed at the city, county and State of New York, this 17th day of May, 1929.

THRASYBULE D. LAZARIDES.
